UNITED STATES PATENT OFFICE.

GEORGE WORDINGHAM, OF MILWAUKEE, WISCONSIN.

TIE AND SOFT-COLLAR CASE.

1,089,519.

Specification of Letters Patent. Patented Mar. 10, 1914.

Application filed September 19, 1911. Serial No. 650,253.

To all whom it may concern:

Be it known that I, GEORGE WORDINGHAM, citizen of the United States, residing at Milwaukee, in the county of Milwaukee and State of Wisconsin, have invented certain new and useful Improvements in Tie and Soft-Collar Cases, of which the following is a specification.

My invention relates to wrappers such as are used for inclosing laundried articles, and particularly to wrappers adapted for inclosing freshly laundried cravats, soft collars or other like articles.

Heretofore no provision has ever been made for individually wrapping up or otherwise protecting freshly laundried cravats or soft collars. These articles because of their length and relatively small width, and because they are not starched, are peculiarly difficult to keep in proper place within a laundry package, and peculiarly difficult to keep unmussed, clean and in proper condition. No means have heretofore been provided for holding ties or soft collars out flat, and the ordinary custom in laundries, in order to keep the cravats and collars in shape, is to place them within a shirt. This is inconvenient inasmuch as when the shirt is used all articles placed within the shirt must be removed therefrom, when one cravat or collar is desired to be used all of the cravats or collars within the shirt must be removed in order to permit the proper article to be selected from the other articles therein, and further than this, in putting these relatively long and narrow soft articles within a shirt it is difficult to prevent mussing the articles and the shirt or soiling the same. With these inconveniences in view an object of my invention is to provide a very simple, effective and practical wrapper for ties, cravats, and soft collars, which may be cheaply made, readily used, and which will entirely protect the articles inclosed therein.

A further object is to provide a wrapper or case for these small articles which shall be sufficiently stiff to hold the cravat or collar in proper position without danger of müssing or wrinkling it.

A further object is to provide a tie or collar wrapper having a translucent or semi-transparent face which will permit the article to be readily observed so that the article does not have to be withdrawn from the wrapper for its characteristics to be noted.

A further object is to provide a wrapper

of the character described which may be easily applied to the article and securely fastened around the same and from which the article may be removed very readily.

My invention is illustrated in the accompanying drawings wherein:

Figure 1 is a rear face view of the wrapper unfolded. Fig. 2 is a rear face view of the wrapper after the cover has been folded around the back and gummed to the rear face of the back. Fig. 3 is an enlarged transverse section on the line 3—3 of Fig. 2. Fig. 4 is a fragmentary perspective view of the lower end of the wrapper and showing a modification. Fig. 5 is a fragmentary longitudinal section of the lower end of the wrapper shown in Fig. 4 in its folded condition.

Corresponding and like parts are referred to in the following description and indicated in all the views of the accompanying drawings by the same reference characters.

2 designates a relatively long and narrow blank of pasteboard or other suitable stiff, thin material forming a back. This back has parallel side edges and the end edges are at right angles to the side edges. The back is somewhat wider than the width of a cravat or soft collar. The outer face of the back is provided with two lines of adhesive 3 and 4. The gum or adhesive surface 4 preferably is disposed at a distance of one-quarter of an inch from the adjacent edge of the back 2. This adhesive may be of any suitable character, but preferably mucilage. Attached to the back by means of the line 3 of adhesive is a covering flap 5 of paper or other light material. Preferably this paper is thin and translucent. One margin of it overlaps the side margin of the back 2, and as before stated, is attached to the back 2 by means of the adhesive 3.

By reference to Fig. 1 it will be seen that the margin 6 of the cover 5 is overlapped upon the margin of the back 2 to a less degree at one end *a* of the back than at the other end *b*. This is for a purpose which will be later disclosed. The cover 5 is not folded over upon the face of the back 2 directly along the line of the edge of the back 2, but the cover is creased along the line 7 and it will be seen that this crease, while approximately parallel to the opposite edge of the cover 5, is not parallel to the adjacent edge of the back 2, but that the distance between the edge of the back 2 and

the crease 7 at one end of the wrapper is considerably less than the like distance at the other end of the wrapper. Thus the crease 7 is angularly disposed relative to the adjacent edge of the back 2.

Before the device is placed in use, the wrapper is in the condition illustrated in Fig. 1 with the cover 5 only attached along one margin to the outer face of the back 2.

- 10 When it is desired to inclose a tie, collar or other article within the wrapper, it is placed upon the stiff back 2 and the paper cover 5 folded over upon the inner face of the back. The paper cover 5 is also formed, in addition 15 to the crease 7, with a crease 8. This crease 8 is not parallel to the crease 7 but the space between the crease 8 and the crease 7 is smaller at the lower end of the wrapper than it is at the upper end. After the article has 20 been placed within the wrapper the adhesive 4 is moistened and the free margin of the cover is pressed down upon the line of adhesive 4. By reason of the fact that the creases 7 and 8 converge as they near the 25 lower end *b* of the wrapper, the wrapper, when the cover is folded over, is larger at its upper end than it is at its lower end so that an article previously deposited within the wrapper may be slipped out from the larger 30 end thereof but is prevented from passing out of the smaller end of the wrapper by reason of the fact that the lower end of the wrapper is contracted relative to the larger end, the cover thus exerts a binding action 35 upon the articles enwrapped and holds these articles securely in place. The articles may be seen through the cover but are held in stiff and rigid condition by means of the stiff and rigid back 2.
- 40 It is to be noted that the back 2 is longer than the cover 5 and projects at opposite ends. This projection protects the edges of the cover and prevents these edges from becoming broken or wrinkled, and further- 45 more, permits the device to be more readily bent or expanded to remove the contents of the package.

Preferrably as shown in Figs. 4 and 5 the lower end of the cover 5 is folded over as at 50 9, thus not only reinforcing the lower edge of the cover, but also providing additional means for preventing the dropping out of the article contained within the cover. This fold 9 projecting upward as it does within 55 the sheath or wrapper formed by folding the cover over upon the back 2, tends to retard any downward movement of the article and thus prevents its being dropped out. It is of course plain that the margin of the cover- 60 ing paper 5 between the fold 8 and the free edge of the cover 5 is relatively wide so that it may be adjusted to accommodate thicker or thinner ties or collars.

The purpose of spacing the line of adhesive from the adjacent edge of the back 2

is to prevent any chance of contact between the dampened adhesive and the goods inclosed within the wrapper. If the adhesive 70 4 were not spaced from the adjacent edge of the back, when the adhesive was dampened, the edge of the back would be liable to be moistened and this moisture might be communicated to the goods or the goods might come in contact with the gum. Furthermore, if the gum was not spaced from the 75 edge, in applying the gum to the back it might be spread upon the edge of the back and possibly upon the face thereof which would bring it in contact with the articles when wrapped up.

It will be seen that the crease 7 is parallel to the edge of the margin 6 of the cover but that by gumming the cover 5 to the back 2 in the manner shown in Fig. 1 so that the overlapping margin 6 is less at one end than at the other, the crease 7 is caused to extend not parallel to the adjacent edge of the back, but at an acute angle thereto as previously stated. It is also obvious that by gumming the cover 5 to the back 2 so that at one end the width of the margin 6 overlapped upon the back 2 is greater than at the other end, the cover when wrapped around the back will be wider at one end than at the other. The complete wrapper 85 not only decreases in width from its upper to its lower end, but also decreases in depth, that is the distance between the inside face of the cover and the adjacent face of the back as shown in Fig. 5 so that the article placed within the wrapper will be wedged 90 therein and will be held in place by frictional engagement with the wrapper.

It will be seen that I have provided a very 100 convenient and effective wrapper for small articles of the character referred to wherein the article may be readily observed and wrapped and in which it is held by contact with the wrapper, the article being prevented from falling downward through the 11 wrapper by reason of the wrapper narrowing as it nears its lower end and the space between the back and cover contracting.

It will further be seen that not only is this 110 wrapper extremely convenient in sending articles home from the laundry, but that the article may be kept within the wrapper until needed and that under these circumstances the articles will be kept from rumpling, creasing, or soiling, and will be in the best 12 possible condition for use. Furthermore, the paper 5 which forms the cover, having been treated so as to render it translucent, is in condition to best protect the ties from the action of moisture in the air.

It is particularly noted that while I do 120 not wish to limit myself to the particular means used by me to form a wrapper having its upper end wider than its lower end, yet preferably the wrapper is formed as pre- 130

viously described and this widening of the upper end is secured by overlapping the margin 6 of the wrapper to a greater extent at the lower end of the back than at its upper end and providing the creases 7 and 8. By this means I am enabled to use a blank for the cover 5 having parallel side edges and do not have to use a blank whose upper end is wider than the lower end. A blank such as last referred to would cause considerable waste and could not be made as cheaply as a blank having parallel side edges.

Having thus described the invention what is claimed is:

A wrapper for laundried articles comprising a back of relatively stiff material and a cover sheet of relatively thin foldable material of greater width than the back, one margin of the cover sheet being attached to

one margin of the back and the other margin of the cover sheet being free, the obverse face of the back being provided with a line of adhesive for the attachment of the free margin of the cover sheet and the said cover sheet having its upper and lower edge portions folded inwardly continuously throughout the entire length of the said end edge portions whereby the folded in edge portions at the upper and lower ends of the wrapper will be closed at the ends of the folds whereby to prevent accidental unfolding of the said edge portions.

In testimony whereof I affix my signature in presence of two witnesses.
